UNITED STATES PATENT OFFICE

FREDERICK W. BURGER, OF NILES, MICHIGAN, ASSIGNOR TO CLARK EQUIPMENT COMPANY, OF BUCHANAN, MICHIGAN, A CORPORATION OF MICHIGAN

APPARATUS FOR MAKING CAST-METAL WHEELS

Application filed August 10, 1925. Serial No. 49,162.

My invention relates to the manufacture of cast metal wheels composed of a spider having a hub portion and integral spokes radiating therefrom, with a rim portion mounted on the outer ends of the spokes. A wheel of this type forms the subject matter of Letters Patent No. 1,691,163 granted November 13, 1928, in the names of Edmund C. Mogford and myself. In my co-pending application for Letters Patent Serial No. 49,161, filed August 10, 1925, for an improved method of manufacturing spiders for such wheels, I have described a method by which the rough casting of the spider is finished to accurate shape and dimensions, so that it is ready to have a rim applied thereto in the manner set forth in the patent above referred to, to Edmund C. Mogford and myself, by a pressing operation, which reduces the machining cost and effects a further considerable saving by eliminating the extra material usually allowed where castings are to be machined, and my present application has to do with the apparatus used in practicing such method. It has for its object to provide improved means by which the spider may be compressed laterally to finished shape and dimensions, and at the same time the ends of the spokes may be properly shaped and sized to receive the wheel rim. I accomplish this object as illustrated in the drawings and as hereinafter described. What I regard as new is set forth in the claims. In this connection I wish it to be understood that while in the accompanying drawings I have illustrated my invention applied to the production of a spider such as that shown and described in the aforesaid patent to Edmund C. Mogford and myself, the use of my improved apparatus is not limited to finishing spiders of that specific design, as it may also be used in connection with spiders of other suitable designs, or for any other purpose for which it is adapted.

In the accompanying drawings,—

Fig. 1 is a vertical section on line 1—1 of Fig. 3 showing my improved apparatus with an untreated spider placed in position to be operated upon;

Fig. 2 is a similar view showing the position of the parts at the end of the operation;

Fig. 3 is a plan view, partly broken away, of the parts shown in Fig. 1;

Fig. 4 is a partial enlarged vertical section of the hub portion of one of the spiders;

Fig. 5 is an enlarged view showing the outer end portion of one of the spokes before treatment; and

Fig. 6 is a similar view showing the same part after treatment.

In the manufacture of wheels of the type referred to, the spider is cast as a unit out of malleable iron or steel. The rough casting comprises a hollow hub portion 7 provided with a central cylindrical passage or bore 8 so that it is annular in form. From the hub portion 7 a suitable number of hollow spokes 9 radiate. These spokes are preferably frusto-conical in form, as shown in Fig. 3, their broad bases merging into the outer wall 10 of the hub portion 7, as shown in Figs. 3 and 4. The inner wall 11 of such hub portion is provided with a circumferential groove 12 in its inner face, preferably approximately midway between the opposite sides of the spider, and the opposite face of the inner wall 11 is rounded or bulged opposite such groove, as shown at 13 in Fig. 4. It will be understood that by the inner face of the inner wall 11 I refer to the face next to the axis of the spider. The side walls 14, 15 of the spider are preferably flat and are parallel with each other, as shown in said figure.

The several spokes 9 are provided at their outer ends with laterally extending pads or seats 16 on which the wheel rim rests after the assembly of the rim with the spider has been effected. In the rough casting these pads have flat outer surfaces, as shown at 17 in Fig. 5, or are curved on an arc of greater radius than the radius of the inner surface of the wheel rim, but as they are designed to fit snugly against the inner surface of the wheel rim when it is applied to the spider, it is necessary that such outer surfaces be rounded or reduced, as 100

shown at 18 in Fig. 6, to conform to the curvature of the inner surface of the rim. To finish such pads to the proper curvature, and also to reduce the hub portion of the spider to the proper thickness, without machining, and by one operation, is the primary purpose of my present invention. In this connection it should be pointed out that in Fig. 4 I have illustrated by dotted lines the original thickness of the hub portion of the rough casting, and in full lines its thickness when finished. This illustration of course is somewhat diagrammatic, as I have not undertaken to show the actual dimensions.

My improved apparatus accomplishes the finishing of the spider, both as to the thickness of the hub portion and the shaping of the pads or other end surfaces of the spokes, by a pressing operation, as will now be more particularly explained.

Referring first to Fig. 1, which shows the relation of the parts before the spider is operated on, but with it in position ready for the operation, 19 indicates a ring die which rests on a suitable base 20. The internal diameter of the lower portion of the die 19 corresponds with the internal diameter of the wheel rim to be applied to the spider, but the upper portion of said die is flared, as shown at 21, to facilitate the movement of the spider thereinto. The base plate 20 is provided at its upper surface with a shoulder 22, which properly positions the die 19 thereon, and also with a raised portion 23 forming an annular shoulder 24 spaced far enough from the shoulder 22 so that the lower portion of a discharge ring hereinafter described may fit between the shoulder 24 and the inner surface of the die 19, as shown in Fig. 2. Mounted centrally on the upper surface of the base 20 is an insert in the form of a block 25, and centrally mounted on the block 25 is a spacing block 26 which rises above the upper face of the block 25 to a distance equal to the finished thickness of the hub portion of the spider. The block 26 serves as a stop to limit the downward movement of the follower hereinafter described.

Arranged centrally above the die 19 in axial alinement therewith is the ram or plunger 27 of a hydraulic press of any suitable description. Said ram is adapted to be reciprocated vertically by hydraulic power, and is provided at its lower end with a punch or follower 28 circular in form and preferably beveled at its outer margin, as shown at 29 in Fig. 1. The greatest external diameter of the follower 28 is substantially equal to the diameter of the spider and the internal diameter of the die 19, as best shown in Fig. 2. The follower 28 is provided at its inner side

which is secured centrally thereto by a bolt 31, as shown in Figs. 1 and 2. The block 30 corresponds in dimensions with the block 25, which it overlies, and both these blocks are made of hardened steel. Their opposing faces are flat and correspond in diameter with the diameter of the hub portion 7 of the spider, as shown in Fig. 2. The follower 28 with its block 30 moves down into the ring die 19 similarly to the action of a male die entering a female die, as will hereinafter appear in the description of the operation of the apparatus.

Suspended from the follower 28 by bolts 32, located at convenient points around the same, is a discharge ring 33, the diameter of which is such that it fits closely in the die 19, as shown in Fig. 2. The discharge ring 33 is designed to support the end portions of the spider during the pressing operation, at which time the pads 16 rest upon its upper surface, as shown in Figs. 1 and 2. The bolts 32 are connected at their lower ends with the discharge ring 33 by means of pivots 34 which pass through eyes in the lower ends of said bolts and are fitted in ears 35 projecting inwardly from the ring 33, as shown in Fig. 1. The upper ends of said bolts are adapted to slide through suitable bearings in the follower 28, and their length is such that when the follower 28 is in its inoperative position shown in Fig. 1, the discharge ring 33 is suspended by the bolts at a distance from the under face of the follower somewhat greater than the width of the pads 16. By this arrangement when the ram 27 is forced down there is some lost motion before the follower 28 comes in contact with the upper surface of the spider; also after the pressing operation the follower first moves up a short distance before the discharge ring 33 begins to rise. The extent of this lost motion may be regulated by means of nuts 36 screwed on the upper ends of the bolts 32, by the removal of which nuts the complete separation of the follower and discharge ring may be accomplished.

In the operation of my improved apparatus, the ram 27 and follower 28 being in the position shown in Fig. 1, a spider is inserted between the follower 28 and the discharge ring 33, so that the outer faces of the pads 16 coincide with the outer face of said discharge ring. The fact that at this time the discharge ring hangs loosely from the follower and is separated therefrom by a distance somewhat greater than the thickness of the spider, permits this to be done easily. The ram 27 is then forced downward, permitting the discharge ring 33 and the spider carried by it to descend through the flared upper portion of the die 19. As has been explained, when the spider is cast the outer faces of the pads 16 are flat or are curved

on relatively large radii, so that they lie in planes that are substantially tangential to the curvature of the wheel rim and also to the curvature of the die 19. Consequently, when the spider is lowered to a certain point, the pads will engage the inner surface of the die, thereby arresting the descent of the spider. Continued downward movement of the ram will permit the discharge ring 33 to continue its descent, leaving the spider supported by the die, until at length the follower 28 will come into contact with the upper surface of the spider, the block 30 engaging the upper surface of the hub portion thereof, while the marginal portion of the follower will engage the upper margins of the pads 16. The further descent of the ram will consequently force the spider down into the narrower part of the die, thereby applying pressure to the pads to curve them into conformity with the curvature of the die, so that they then assume the shape shown in Fig. 6. As the spider is carried down into the die, the lower face of its hub portion comes into contact with the block 25, the parts then being in the position shown in Fig. 2, so that the hub portion is compressed between the blocks 25 and 30. The pressure thus applied to the spider reduces the thickness of the hub portion to an extent determined by the height of the stop block 26, and at the same time the upper and lower marginal portions of the pads are compressed to the desired finished dimensions. The purpose of providing the groove 12 in the inner wall of the hub portion of the spider is to get away from a continuous cylindrical wall and allow all distortions to take place at the curved portion, thereby making it possible to press the hub together slightly in order to reduce it to the proper thickness, as well as to make the two sides parallel and iron them out. The inner and outer walls 13 and 10 of the hub portion are made comparatively thin to facilitate this operation, but of course they are thick enough to have the requisite strength.

It will be noted that the first step of forcing the spider into the circular die 19 sizes and shapes all of the pads simultaneously, and in so doing sets up inwardly acting pressures in the entire spider. The second step of thereafter applying pressure to the opposite sides of the hub portion in an axial direction sets up pressures in the spokes and pads acting outwardly in the spokes, tending to force the pads out against the sides of the ring die with an increased pressure. This naturally follows from the compression of the hub portion, owing to the fact that the annular form of the inner wall 11 and the considerable mass of metal therein will substantially prevent inward contraction of the hub portion. Moreover, the

bulged or V-shaped cross-section of the outer wall 10 will result in the axial compression of the hub portion reacting outwardly as a radial thrusting pressure tending to force the pads out against the sides of the circular die. Thus the latter step of compressing the hub portion serves the two-fold purpose of sizing and shaping the hub portion and also of creating outwardly acting pressures in the spokes. The advantage gained by creating these outwardly acting pressures is illustrated in the case of a spider wherein one spoke is slightly shorter than the others. The initial step of forcing the spider into the ring die may not subject this spoke to the same amount of inwardly acting pressure as it will the other spokes. However, the secondary step of compressing the hub portion will set up outwardly acting pressures in the shorter spoke which will cause the same to be pressed outwardly against the circular die 19 with the required pressure to shape and size the pad thereof correspondingly with the other pads. It will be noted that at no time in the entire die operation do either of the die parts contact with the intermediate portions of the spokes, and, hence, the spokes are only subjected to end-wise compression stresses which they are capable of sustaining without possibility of fracture.

An interesting phenomenon occurs as a result of the above described operation of compressing the spider, which phenomenon aids most decidedly in producing a more durable wheel. The act of compressing the spider apparently stores a potential or inherent elasticity in the molecular structure thereof, which is released by the action of vibration, with the result that spider tends to return to its former size, thereby creating and maintaining a heavy pressure grip with the felloe surrounding the spoke ends. Consequently in a wheel built up of one of these compressed spiders, the jar and vibration inherent in the use of the wheel permits the spider to increase in diameter, so that the spider actually becomes tighter in the felloe as the wheel is being used.

From the foregoing description it will be seen that by the single pressing operation described the correct diameter across the spokes is produced, and the outer faces of the pads are caused to conform to a true circle; at the same time the hub portion of the spider is reduced to the proper thickness and its sides are made parallel and smoothed out. Therefore no machining is necessary, and, besides, by eliminating that work a considerable saving is effected through reduction in the weight of the casting.

The die ring 19 may be made of hardened steel, but I prefer to make it of soft steel and to provide it with shoes or inserts of

hardened steel at the points where it is engaged by the pads of the spokes. These shoes are shown at 37. They are merely hardened steel blocks inserted in vertical grooves in the die ring 19 so that they may be removed and replaced if necessary, or instead of replacing them they may be set up to compensate for wear by means of shims used in the ordinary way.

10 What I claim as my invention and desire to secure by Letters Patent, is—

15 1. In apparatus for sizing and shaping wheel spiders of integral hub and spoke construction, the combination of a ring die having a conical surface at the outer end of the die and a substantially cylindrical surface extending from said conical surface back into the die adjacent to the inner end thereof, a follower having a thrusting surface at its outer edge, adapted to bear against the ends of the spider spokes at the side edges thereof, means for producing relative axial movement between said ring die and said follower for forcing the spider axially into said ring die to compress the spider radially and to shape the peripheral portions of the spokes by relative transverse sliding movement of the spokes across said conical and said substantially cylindrical surfaces of the ring die, and coacting die surfaces on said follower and at the inner end of said ring die for compressing the hub portion of the spider and thereby expanding the spider radially after said spider has been forced 35 into the substantially cylindrical inner portion of the ring die.

20 2. An apparatus for shaping wheel spiders comprising a female die having tapered die surfaces adapted to contact directly with the peripheral portion of the spider, a male die for forcing the spider axially into said female die whereby the relative movement between the spider and said tapered die surfaces transversely across the peripheral portion of the spider will first shape the peripheral portion of said spider, and coacting die surfaces on said dies for compressing the hub portion of the spider therebetween after the spider has been forced to the end 50 of its axial movement in said female die.

25 3. An apparatus for shaping wheel spiders comprising a ring die having an outwardly flaring opening at one end for centering the spider and having die surfaces of greater depth than the peripheral width of the spider, means for causing movement of said spider into said die for radially pressing the peripheral portions of said spider inwardly in an initial shaping operation, and means associated with the inner end of said ring die and cooperating with said last named means for laterally pressing the hub portion of said spider in a secondary shaping operation, the compression of 60 said hub portion creating outwardly acting

pressures in the spokes of the spider for aiding in shaping and sizing the peripheral portions thereof.

4. An apparatus for shaping wheel spiders comprising a ring die having a flared opening at its outer end and a closed inner end, follower means cooperating with said ring die, means causing relative movement between said ring die and said follower means to force the spider through the flared open end and back towards the closed end of said ring die whereby the relative movement between the ring die and the spider in a direction transversely across the spider radially presses the peripheral portions of 75 said spider, and means associated with said ring die and cooperating with said follower means for laterally compressing the hub portion of said spider only after said spider has been forced entirely within said ring die. 85

5. An apparatus for shaping wheel spiders comprising a ring die having substantially cylindrical side walls and a laterally divergent opening at the outer portion thereof, follower means for forcing the spider into the divergent opening of said ring die, means for producing relative movement between said ring die and said follower means, said follower means exerting pressure on the spoke ends and hub portion of 95 the spider without exerting pressure on the intermediate portions of the spokes, a block adjacent the opposite end of said ring die and cooperating with said follower means for exerting lateral pressure on said hub portion, and stop means for limiting the extent to which said hub portion may be compressed. 100

6. An apparatus for shaping wheel spiders comprising a pair of dies, means for causing relative movement between said dies to force the spider into one of said dies, and means engaging the outer portion of the spider and utilizing the relative separating movement between said dies for discharging 110 the spider from the die into which it has been forced.

7. An apparatus for shaping wheel spiders comprising a ring die element, a follower element, means for producing relative movement between said elements in the sizing operation, and means engaging the outer ends of the spokes of said spider and utilizing the relative separating movement between said elements for discharging the 120 spider from the same end of said ring die element into which it has been forced.

8. An apparatus for shaping wheel spiders comprising male and female dies superposed one above the other with the lower die held substantially stationary and the upper die supported for movement relative thereto for forcing the spider into the female die, a discharge member for discharging the spider from said female die, and means 130

adapted to extend through the spider for supporting said discharge member from said upper movable die.

9. An apparatus for shaping wheel spiders comprising a circular die element, a co-operating die element, means for causing relative movement between said elements for forcing the spider into said circular die element, a discharge member utilizing the relative separating motion between said die elements for discharging the spider from said circular die element, and lost motion supporting means for supporting said discharge member on one of said die elements.

10. An apparatus for shaping wheel spiders comprising male and female dies superposed one above the other, means for causing relative movement between said dies for forcing the spider into said female die, a discharge member for ejecting the spider from said female die, and supporting rods for said discharge member extending through holes in the upper die for movably supporting said discharge member thereon.

11. An apparatus for shaping wheel spiders comprising male and female dies superposed one above the other with the lower die held substantially stationary and the upper die supported for movement relative thereto, a discharge member for ejecting the spider from said female die, and a plurality of rods attached at their lower ends to said discharge member and passing loosely up through openings in the upper die for suspending said discharge member from said upper die.

12. An apparatus for shaping wheel spiders comprising a follower, means moving with the follower for supporting the spider below the follower, a block adapted to bear against one side of the hub portion of the spider, and a block carried by the follower and adapted to bear against the other side of said hub portion for applying lateral pressure thereto.

13. An apparatus for shaping wheel spiders comprising a follower, means movable relative to the follower for supporting the spider from the follower, a block adapted to bear against one side of the hub portion of the spider, a block carried by the follower and adapted to bear against the other side of said hub portion for applying lateral pressure thereto, a ring die concentric with said blocks, and means for actuating the follower to move the spider into said die to shape the peripheral portions thereof and to compress the hub portion thereof between said blocks.

14. An apparatus for shaping wheel spiders comprising a follower, means suspended from the follower for supporting the spider, a ring die, and means for actuating the follower to move the spider into said die to shape the peripheral portions

thereof, and to withdraw the spider from said die.

15. An apparatus for shaping wheel spiders comprising a follower, means suspended from the follower for supporting the spider, a ring die, means for actuating the follower to move the spider into said die to shape the peripheral portions thereof, and to withdraw the spider from said die, a block adapted to bear against one side of the hub portion of the spider, and a block carried by the follower and movable into engagement with the opposite side of said hub portion and cooperating with said first mentioned block to compress said hub portion.

16. An apparatus for shaping wheel spiders comprising a follower, means suspended from said follower for supporting the spider, said supporting means being movable toward and from the follower, a block adapted to bear against one side of the hub portion of the spider, and a block carried by the follower and movable into engagement with the opposite side of said hub portion to compress the same between said blocks.

17. An apparatus for shaping wheel spiders comprising a follower, means suspended from said follower for supporting the spider, said supporting means being movable toward and from the follower, a ring die, and means for actuating said follower to move the spider laterally into said die to shape the peripheral portions thereof.

18. An apparatus for shaping wheel spiders comprising a follower, means suspended from said follower for supporting the spider, said supporting means being movable toward and from the follower, a ring die, means for actuating said follower to move the spider laterally into said die to shape the peripheral portions thereof, a block adapted to bear against one side of the hub portion of the spider, and a block carried by the follower and movable into engagement with the opposite side of said hub portion to compress the same between said blocks.

19. An apparatus for shaping wheel spiders comprising a follower, a discharge ring adapted to support the spider, means connecting said discharge ring with the follower to move toward and from the same, a ring die, and means for actuating the follower to move said discharge ring and the spider laterally into said die.

20. An apparatus for shaping wheel spiders comprising a follower, a discharge ring adapted to support the spider, means suspending the discharge ring from the follower to move toward and from the same, a block adapted to bear against one side of the hub portion of the spider, and a block carried by the follower adapted to bear

against the opposite side of said hub portion.

21. An apparatus for shaping wheel spiders comprising a follower, a discharge ring adapted to support the spider, means suspending the discharge ring from the follower to move toward and from the same, a block adapted to bear against one side of the hub portion of the spider, a block carried by the follower adapted to bear against the opposite side of said hub portion, a ring die, and means for actuating the follower to move said discharge ring and the spider laterally into said die to shape the peripheral portions of the spider and compress the hub portion thereof between said blocks.

22. In apparatus for sizing and shaping integrally cast wheel spiders before they are mounted in the wheel felloes, the combination of a ring die having a conical surface at the outer end thereof and a substantially cylindrical surface extending from said conical surface back into the die, said surfaces being of greater depth than the peripheral width of the spider, a follower of lesser diameter than said cylindrical surface for moving into said ring die, said follower having a thrusting surface at its outer edge adapted to bear against the ends of the spider spokes at the side edges thereof, means for producing relative axial movement between said ring die and said follower for forcing the spider axially into said ring die to compress the spider radially and to shape the peripheral portions of the spokes by relative transverse sliding movement of the spokes across said conical and said substantially cylindrical surfaces of the ring die, and coacting die surfaces on said follower and at the inner end of said ring die for compressing the hub portion of the spider after said spider has been forced into the inner portion of said ring die, the die surfaces of said ring die comprising shoes set at angularly spaced points in the ring die to be engaged by the ends of the spider spokes.

FREDERICK W. BURGER.

23. In apparatus for sizing and shaping integrally cast wheel spiders before they are mounted in the wheel felloes, the combination of a ring die having a conical surface at the outer entering end of the die and a substantially cylindrical surface extending from said conical surface back into the die, a follower having a thrusting surface adapted to bear against the ends of the spider spokes at the side edges thereof, means suspended from said follower for supporting the spider, said supporting means being movable toward and from the follower, means for producing relative axial movement between said ring die and said follower for forcing the spider axially into said ring die to compress the spider radially and to shape the peripheral portions of the spokes by relative transverse sliding movement of the ends of the spokes across said conical and said substantially

cylindrical surfaces of the ring die, coacting die surfaces on said follower and at the inner end of said ring die for compressing the hub portion of the spider after said spider has been forced into the substantially cylindrical inner portion of the ring die, and stop means for limiting the extent to which said hub portion may be compressed.

24. In apparatus for sizing and shaping integrally cast wheel spiders before they are mounted in the wheel felloes, the combination of a ring die having a conical surface at the outer end of the die, a follower having a thrusting surface adapted to bear against the ends of the spider spokes at the side edges thereof, means for producing relative axial movement between said ring die and said follower for forcing the spider axially into said ring die to compress the spider radially and to shape the peripheral portions of the spokes by relative transverse sliding movement of the spoke ends across the die surfaces of the ring die, and coacting die surfaces on said follower and at the inner end of said ring die for compressing the hub portion of the spider after said spider has been forced into the inner portion of said ring die, the die surfaces of said ring die comprising shoes set at angularly spaced points in the ring die to be engaged by the ends of the spider spokes.
